UNITED STATES PATENT OFFICE.

HENRY HILLEBRAND AND MORETON JACK, OF NEW YORK, N. Y.

PRESSURE-REGULATOR.

No. 919,013.

Specification of Letters Patent.

Patented April 20, 1909.

Application filed March 18, 1908. Serial No. 421,896.

To all whom it may concern:

Be it known that we, HENRY HILLEBRAND, a citizen of the United States, and a resident of the city of New York, borough of Manhattan, in the county and State of New York, and MORETON JACK, a citizen of the United States, and a resident of the city of New York, borough of Brooklyn, in the county of Kings and State of New York, have invented 10 a new and Improved Pressure-Regulator, of which the following is a full, clear, and exact description.

This invention relates to regulating devices such as are used for controlling the operation of a motor driving a pump which supplies a reservoir.

The object of the invention is to provide means for automatically starting and stopping the operation of the pump controlled 20 by the condition of the reservoir.

The specific object of the invention is to provide an arrangement in which the operation of the electric motor is controlled through the medium of a main switch controlled by solenoid coils, which is itself controlled by a secondary or auxiliary switch operated directly by a pressure regulator or gage. The switch contacts and circuits are arranged in such a way that the instant that 30 the pressure in the reservoir arrives at a predetermined point, the main switch will be thrown, and the current through both switches will be instantly cut off whatever may be the immediate condition of the reservoir.

A further object of the invention is to provide a circuit arrangement which will operate in such a way that when a predetermined pressure exists in the reservoir, the 40 motor will not only have its driving current cut off, but it will be short-circuited upon itself so that the electromotive force which it generates will have a braking effect upon it. In this way the motor is made to stop 45 instantly, and there is no danger of the pressure rising or falling materially below the predetermined points.

The invention consists in the construction and combination of parts to be more fully 50 described hereinafter and particularly set forth in the claims.

Reference is to be had to the accompanying drawing forming a part of this specification, which represents the apparatus and 55 wiring, diagrammatically.

Referring particularly to the parts, 1 and

2 represent the line wires from the main which lead in to a double switch 3. From the switch a conductor 4 leads in to the binding post 5 of an electric motor 6. From the 60 motor a conductor 7 leads through a switch 8 which is normally in the position shown, but which may be thrown over to a contact 9 on a conductor 10 which leads from the main switch 11. In this way the regulating apparatus may be cut out of circuit, with the motor remaining in circuit. The conductor 7 leads to the pivot 12 of the main switch, and this switch comprises a lever 13, the upper arm whereof is adapted to be thrown into 70 either of its operative positions by means of a yoke 14 of insulating material, secured between two solenoid cores 15 and 16. These solenoid cores 15 and 16 are in longitudinal alignment with each other; the core 15 extends toward the left and is controlled by a solenoid coil 17, and a similar coil 18 controls the core 16. The conductor 10 which has been referred to above, leads to a contact plate 19 which is mounted on an insulating 80 block 20, and cooperates with the lever 13. A similar contact plate 21 is mounted on the same block 20, and this contact plate also cooperates with the lever 13, as will be readily understood. The coil 17 is connected with 85 the conductor 4, that is, with the positive leg of the main circuit, by a conductor 22, and this conductor has a branch conductor 23 which is connected with the contact plate 21. From the conductor 10 near the switch 11 90 a conductor 24 connects with the coil 18.

The motor 6 is adapted to drive a pump 25 which charges a reservoir 26. From this reservoir 26 a main pipe 27 leads, which is connected by a suitable pipe 28 with a regulator 95 29. This regulator 29 is of common form, presenting a case 30 in which there is mounted a flexible diaphragm 31, on the under side of which pressure is exerted by the air which flows in to the case from the pipe 28. To the 100 diaphragm 31, which is of rubber or similar material, a vertically extending stem 32 is attached, which passes upwardly from the device, and around this stem a spring 33 is placed, which thrusts against the diaphragm 105 and tends to hold it in an extreme low position. The upper end of this stem 32 is formed into an insulated bar 34, which bar has a contact finger 35 extending laterally therefrom. This contact finger slides up and down on an insulated block 36 having contact plates 37, 38 and 39 thereupon. The

contact 37 is connected by a conductor 40 with the coil 17, and a short conductor 41 connects the contacts 37 and 38 as indicated. The contact plate 39 is connected by a conductor 42 with the coil 18. The insulated bar 34 is connected by a short conductor 43 with the main conductor 7. The drawing shows the regulator bar 34 in its normal position, at which time the contact finger 35 will rest on the insulated block between the contacts 37 and 39.

The operation of the apparatus will now be described: Under normal conditions, the main circuit is closed through the motor, and 15 is as follows: from the line wire 1, through switch 3, conductor 4, binding post 5, through the motor 6, conductor 7 and switch 8, to the pivot 12 of the switch 11. From this point, through contact plate 19, conductor 10, switch 3, to the line wire 2. When the pressure in the reservoir 26 and pipe 27 rises to the maximum limit, the finger 35 will strike the contact 37, at which time the following circuit will be made: conductor 22, 25 coil 17, conductor 40, contact plate 37, finger 35, regulator bar 34. From this regulator bar the current passes over a flexible conductor 43^a, which constitutes a part of the conductor 43. From the conductor 43 the current 30 passes along the conductor 7 through the pivot 12 of the switch, and then from this switch, by the conductor 10 to the line wire 2. The current flowing through this circuit energizes the solenoid coil 17, drawing in the core 15 thereof. This throws the lever 13 over to its opposite position, upon the contact 21. This breaks the circuit through the motor, and also through the solenoid coil 17. The motor having been cut out in this way, 40 the pump stops, and the pressure in the reservoir 26 gradually falls. The switch 11, however, will remain in this position.

When the pressure drops to the normal minimum limit, the contact finger 35 will 45 touch the contact plate 39. When this takes place, the following circuit will be made: conductor 4, conductors 22, 23, contact 21, lower part of lever 13, pivot 12, conductor 7, conductor 43, 43^a, contact bar 34, 50 finger 35, contact 39, conductor 42, coil 18, conductor 24, conductor 10, back to the line. It will be remembered that the switch 11 is then in its opposite position from that in which it is represented in the figure. This 55 closes the circuit through the coil 18, which becomes energized and moves the switch back to the position in which it is shown in the figure; that is, the motor circuit will again be closed. In this way the motor will 60 automatically be started up when the pressure falls to the low limit, and will be automatically stopped when the pressure rises above the high limit. If the pressure should suddenly fall, by the bursting of a pipe or 65 other cause, below the low limit, the regula-

tor bar 34 will suddenly descend and the contact finger 35 will make a circuit through the contact plate 38. This circuit will be the same as in the first instance, passing to the contact 40 by the conductor 41 from the 70 plate 38. It should be borne in mind that the switch 11 will be in the position shown in the figure, for that is the position to which the switch will be thrown as the contact finger 35 crosses the contact plate 39. Closing 75 the circuit through the coil 17 in this way, of course, opens the circuit through the motor by throwing the lever 13 over to the contact plate 21. The yoke 14 is mounted to slide upon a guide 14^a which has stops 14^b at its 80 ends which limit its movement.

Attention is called to the fact that when the main switch has opened to stop the motor a closed circuit is formed through the motor 6, the conductor 7, switch lever 13, contact 21, conductor 23, conductor 22, back to the motor. The motor runs in this circuit on its momentum as a generator and quickly comes to a stop through the braking effect of generating current. This braking action is 90 very advantageous as it produces a very uniform regulation of the pressure. If the motor were permitted to continue to revolve, the action of the pump would still continue and the pressure would continue to increase 95 above the point at which the regulator acted. With the circuits shown, the pump stops instantly. This is a very desirable mode of operation where the pressure used is small and the variation slight. Furthermore, it 100 enables the device to be used with a comparatively small reservoir for the air. Attention is called to the fact that with this circuit arrangement, the circuit is never broken at the controlling switch, that is, at the regulator 105 switch, and this is highly advantageous for it prevents sparking at the controlling switch which would tend to burn away the contact finger 35. As there is no sparking at this point, a very delicate contact finger can be 110 employed, which affords little or no resistance to the movement of the stem of the regulator, and this feature operates to increase the delicacy and sensitiveness of the apparatus, making it especially useful in very low 115 variations, such as a half pound to the square inch, which is common in beer pump operation.

Having thus described our invention, we claim as new and desire to secure by Letters 120 Patent:

1. In apparatus of the class described, in combination, a reservoir, a motor, a pump driven thereby, a pressure regulator connected with said reservoir, a main switch having a lever, a closing coil and an opening coil for moving said lever, a contact co-operating with said lever to close the main circuit through said motor, a second contact connected with said opening coil and co-operating 130

with said lever to form a normally incomplete circuit through said lever and said opening coil, a second normally incomplete circuit passing through said lever and said closing coil, and means for closing either of said normally incomplete circuits controlled by said pressure regulator.

2. In apparatus of the class described, in combination, a reservoir, a motor, a pump driven thereby, a pressure regulator connected with said reservoir, a main switch having a lever, a contact coöperating with said lever to close the main circuit, said switch having a second contact coöperating with said lever, a closing coil independent of said contacts to move said lever, an opening coil connected with said second contact to move said lever, and means for closing a circuit through either of said coils and said lever controlled by said pressure regulator.

3. In apparatus of the class described, in combination, a reservoir, a motor, a pump driven thereby, a pressure regulator connected with said reservoir, a main switch, an electromagnet having two opposing coils and controlling said main switch, a main circuit normally closed through said motor and said main switch and excluding both of said coils, means for closing said main circuit through either of said coils actuated by said pressure regulator, and means for forming a closed circuit through said main switch when in its open position passing through said motor whereby said motor brakes upon itself and stops said pump.

4. In apparatus of the class described, in combination, a reservoir, an electric motor, a pump driven thereby for charging said reservoir, a main switch, a pressure regulator connected with said reservoir, contacts controlled thereby, coils for opening and closing said main switch, circuits connecting said contacts with said switch, coils for controlling said main switch, and means for closing a circuit through said motor when said main switch is in open position whereby said motor produces a braking effect upon itself.

5. In apparatus of the class described, in combination, a reservoir, an electric motor, a charging device for said reservoir driven by said motor, a pipe leading from said reservoir to the delivery point, a pressure regulator on said pipe, an electromagnet having a pair of

opposing coils, a switch lever, a contact coöperating with said lever, a main circuit passing through said motor, a circuit connecting said contact with one of said coils and passing through said motor, a second contact, a circuit connecting the same with the other of said coils passing around said motor and connecting with said main circuit to form a short braking circuit through said motor, and means actuated by said regulator for closing either of said circuits.

6. In apparatus of the class described, in combination, an electric motor, a reservoir, a pump actuated by said motor, a main switch having an opening coil, a closing coil, a lever controlled by said coils, a pair of contacts coöperating with said lever, a conductor connecting said motor with said lever, a main conductor leading current to said motor, a conductor leading from said main conductor around said motor connecting with one of said contacts and connecting with said opening coil, a pressure regulator, a conductor connecting said regulator with said opening coil, a conductor connecting said closing coil and the other of said contacts in parallel, a conductor leading from said pressure regulator and connecting to the conductor connecting said motor with said lever, and a conductor connecting said regulator with said closing coil.

7. In apparatus of the class described, in combination, an electric motor, a pump operated thereby, a reservoir, a pressure regulator, a main switch having a lever, an opening coil and a closing coil for controlling said lever, a main circuit normally passing through said motor, said lever and one of said contacts, a circuit connecting said opening coil with the other of said contacts and passing through said regulator, and a circuit passing through said closing coil and connecting the same with said regulator, said regulator forming a switch coöperating with said main switch.

In testimony whereof we have signed our names to this specification in the presence of two subscribing witnesses.
